UNITED STATES PATENT OFFICE

THEODORE C. RIEBE, OF CHICAGO, ILLINOIS, ASSIGNOR, BY MESNE ASSIGNMENTS, TO ASSOCIATED ELECTRIC LABORATORIES, INC., OF CHICAGO, ILLINOIS, A CORPORATION OF DELAWARE

PAYSTATION EQUIPMENT

Application filed March 6, 1929. Serial No. 344,689.

- The present invention relates in general to multi-coin paystation devices designed for use in conjunction with and as a part of the substation equipment of a subscriber's line in an automatic telephone system. More specifically, the invention is concerned with the provision of a unitary multi-coin paystation device in which the deposit of a coin need not be made until the subscriber called responds, or, in the case of a toll connection, until the toll operator has obtained a desired party and requested the calling subscriber to deposit the coin or coins necessary to pay for the toll connection.
- In automatic telephone systems the use of paystations, of the type disclosed in the Madsen Patent 1,556,948, have proven quite satisfactory. However at some such stations, where many toll calls are initiated, it is quite advantageous to provide means whereby coins can also be collected to pay for such connections. This need has heretofore been met, after a fashion, by increasing the size of the base upon which the paystation shown in the Madsen patent was formerly mounted, and mounting thereon such a paystation together with a multi-coin receiving box containing only coin actuated signal devices, such, for instance, as those used in the paystation apparatus disclosed in the Forsberg and Long Patents Nos. 1,043,219 and 1,383,472.
- With such an arrangement local calls are extended as formerly; i. e., by the deposit of a coin in the single slot device upon the response of the called subscriber. If a toll call is set up the operator instructs the subscriber to deposit the required coin or coins in the multi-coin device and supervises the deposit of the coins by listening to the coin actuated signals as is done in supervising the deposit of coins in a pay station such as shown in the previously mentioned Forsberg and Long patents.
- The foregoing arrangement is more in the nature of a make-shift rather than being a real solution to the problem, in that the provision of two coin boxes leads to confusion as to which to use; the two devices take up too much wall space; and the use of two devices where one should suffice objectionably increases the cost of the substation equipment.
- The paystation apparatus, as shown in Fig. 1, is of the same general construction and appearance as those disclosed in the Forsberg and Long patents. The apparatus within the structure shown in Fig. 1 having to do with the transmission of signals in response to the deposit of coins is also similar to that shown in the Forsberg and Long patents and therefore has not been disclosed in the instant application. Since in the present invention no coin collect or refund operations are necessary, all apparatus of this character is omitted, but the downwardly projecting extension, of the armature of the polarized magnet, formerly used for these operations, is used instead for controlling the operation of an additional set of contact springs similar to those actuated by the polarized magnet disclosed in the Madsen patent.
- The invention is disclosed in two sheets of drawings, comprising Figs. 1 to 5, inclusive. Fig. 1 is a front view of the device, in elevation; Fig. 2 diagrammatically illustrates the circuits and apparatus; Fig. 3 is a front view, in elevation of the electro-magnetic part of the mechanism in normal position; Fig. 4 is a rear view of Fig. 3 in elevation with certain parts omitted for sake of clearness and with the various parts shown in operated position; while Fig. 5 is a view of a portion of Fig. 3 as seen from the left. It also shows a section of a portion of an associated coin chute.
- Referring now to Figs. 2-5, inclusive, a detailed description will be given of the polarized magnet and its associated parts, after

which will follow a description of the operations as they occur in practice.

The structure of the polarized magnet is substantially like that shown in the previously mentioned Forsberg patent, except for the fact that, as previously stated, since no coin collecting or refunding operations are necessary the apparatus for bringing about such operations has been omitted.

- 10 The magnet armature 11 is carried by a bracket 12 which is pivotally supported in the frame plate 23. The member 12 has armature stop members 12³, a spring actuating arm 12', shown in Figs. 2 and 3 and an 15 arm 12², shown in Figs. 2, 4 and 5, to which is secured an extension 11' pivotally supporting a spring actuating arm 13.

The free end of arm 13 is supported by a small bracket 18 secured to a double arm lever 20, which is also pivotally secured to upwardly extending portions of the previously mentioned plate 23. The lever 26 functions in substantially the same manner as does the lever 113 of the Forsberg patent previously 25 referred to. The arm 27 of the lever 26 is moved into the position in which it is shown in Figs. 3 and 5 by the bushing on extension 12' of the armature plate 12. And although a tension spring 32 tends to move the arm 27 30 and close contact springs 29, upon movement of the armature 11 to its reverse position, the movement of arm 27 is prevented by the coin trip lever 30. The deposit of a coin in the coin chute, however, will cause the lever 30 to 35 momentarily swing out of the path of movement of arm 31 and permit the tension spring 32 to rotate the lever 26 to cause its arm 27 to close contact springs 29.

The actuation of the armature 11 to its alternate position causes the springs 19 to be 40 closed by armature extension 12'; causes the arm 11' to move the spring actuating arm 13 to the right, as viewed in Figs. 2 and 3 and with it the tension of spring 33 into the position in which it is shown in Fig. 4. The 45 movement of the spring 33 away from the bushing on spring 16 permits the tension of spring 16 to become effective to bring this spring and the associated springs 14 and 15 50 into contact with each other. When a deposited coin actuates lever 30 and causes the lever 26 to be rotated in the manner previously mentioned, not only are the contacts 29 closed, but also the free end of lever 13 is 55 slightly elevated by rotation of the bracket lever 26 sufficiently to cause the bracket 18 to move the arm 13 clear of the top of spring 33. Spring 33, therefore, again becomes effective to overcome the tension of spring 16. 60 This results in the springs 14, 15 and 16 again being separated.

If now the armature is restored to its initial position, as shown in Figs. 1, 2, 3 and 5, the bushing on extension 12' of the armature 65 plate 12 will rotate the lever 26 clockwise; the

arm 27 will again force the tension spring away from contact springs 29, permitting them to open the short circuit around winding 24; lever 18 will be again lowered permitting arm 13 to again drop behind spring 33; and the arm 27 will be elevated sufficiently to permit coin actuated arm 30 to restore, by gravity, to its normal position.

In view of the foregoing description and of the disclosures in the patents hereinbefore referred to, it is believed that the invention can be most readily made clear by describing its mode of operation in a typical installation.

Referring now to Fig. 2, it will be assumed that the subscriber at substation A desires to set up a connection to some other local subscriber of the system. Upon the removal of the receiver 20 at substation A, a circuit is closed, over which current from the exchange battery (which is normally bridged across the line conductors 1 and 2, in series with the line relay associated with the calling line) flows as follows: from the exchange over line conductor 1 on the right of the condenser 6, by way of branch conductor 3, the winding 24 of the polarized magnet, to the branch of the line conductor on the left hand side of condenser 6, through the switch hook springs 8, impulse springs 7 of the calling device CD, transmitter 9, primary winding of induction coil 22 to line conductor 2, and thence to the exchange. As a result of the closure of this circuit the calling line conductors 1 and 2 are extended to the line relay of an idle selector or connector switch, depending upon the capacity of the system. The removal of the receiver also closes the receiver circuit, which is a local circuit including the switch hook 21, the receiver 20, transmitter 9, impulse springs 7, springs 8, the winding 24 of the polarized relay, the condenser 6', and the secondary winding of the induction coil 22.

Although the winding 24 of the polarized magnet is included in the above-described circuits, this magnet is not energized at this time due to the normal current flow being in the wrong direction.

The calling subscriber may now proceed to manipulate the dial of his calling device CD in accordance with the digits of the number of the substation desired, whereby the automatic switches used in extending the connection are operated in any well known manner to complete the desired connection. During the operation of the calling device the shunt springs 10 are closed to short circuit the receiver and transmitter. This is the usual provision made to reduce the resistance and impedance of the line circuit during the transmission of impulses, and to prevent noises in the receiver during the dialling operation.

When the called subscriber responds to the

call, the back-bridge relay of the connector used in seizing the called line responds and reverses the line conductors 1 and 2 as regards their battery connections. Current now flows over the line circuit and through the winding 24 of the polarized magnet in the reversed direction. This reversal of the current in winding 24 of the polarized magnet causes it to rotate its armature in a clockwise direction, that is, toward the core of coil 24. When the armature is attracted in this direction it carries the arm 13 to the right, permitting the springs 14, 15, and 16 to come into engagement. The armature itself, through the medium of extension 12', also closes springs 19, and places the springs 29 under the control of the coin actuated lever 30. The engagement of springs 14, 15 and 16 short circuits the transmitter 9, and connects the resistance 17 in a shunt circuit across the receiver 20. The short circuiting of the transmitter makes it impossible for the calling subscriber to talk to the called subscriber through the medium thereof, while the resistance 17 prevents the subscriber using the receiver as a transmitter, but does not prevent the calling subscriber from hearing the called subscriber answer.

When the calling subscriber hears the called subscriber answer, he deposits a coin in the coin chute. The weight of the coin striking lever 30 causes this lever to release the arm 27' of lever 26, which, under the tension of spring 32 now closes springs 29 and raises arm 13 above the top of the tension spring 33, thereby allowing springs 14, 15 and 16 to again separate. Springs 29 in closing place a direct short circuit around the winding 24 so as to exclude it from the talking circuit. The separating of the springs, 14, 15, and 16 leaves the talking circuit for the calling substation in normal condition, and the two subscribers may converse over the circuits represented by the heavily drawn lines.

After the conversation is completed, the calling and called subscribers replace their receivers.

It will be recalled that when the called subscriber responded the operation of armature 11 of the polarized relay resulted in the closure of springs 19. The closure of these springs completed a circuit extending from line conductor 1 at the right of condenser 6, through springs 19, winding 25 of the polarized magnet, the impulse springs 7, transmitter 9, and the primary winding of the induction coil 22 to the line conductor 2. This circuit is for restoring the paystation apparatus to normal, and it is not effective while the receiver is off the hook at the station A, as winding 25 is short circuited by a circuit extending from the lower terminal of winding 25, through the springs 19 and 29, and the

closed switch hook springs 8, back to the upper terminal of winding 25.

When the calling subscriber replaces his receiver, this short circuit is removed at switch hook springs 8, leaving the winding 25 in bridge of the line conductors 1 and 2.

If the called subscriber has not as yet replaced his receiver upon the switch hook, nothing further happens at the exchange, as the current flow is still in the direction appropriate for rotating armature 11 clockwise. However, as soon as the called subscriber's receiver is replaced upon the switch hook the direction of current flow over conductors 1 and 2 and through the winding 25 is restored to normal. When this occurs the armature 11 is attracted to the core of the winding 25. In this movement of the armature, its springs 19 are again separated and the arm 27 of lever 26 is forced away from the springs 29, permitting them to again separate. The movement of lever 26 to its initial position permits lever 30 to restore by gravity to its initial position, to again lock the lever 26 independent of the armature 11 and to permit the lever 13 to again drop back of the tension spring 33. The opening of springs 19 interrupts the bridge formerly extended across line conductors 1 and 2 and including the winding 25, permitting the central exchange apparatus to restore to normal in the usual and well known manner.

When the subscriber at substation A desires to make a toll call the connection is set up in the same manner as for a local call, but the switches which extend a connection to an operator do not reverse the direction of current flow to the calling line, consequently the polarized apparatus is not operated and the calling subscriber is therefore not required to deposit a coin to converse with the toll operator.

Since the paystation device is equipped with openings for receiving different sized coins and with signalling devices actuated by the deposit of coins, the toll operator at any time she desires may request that the calling subscriber deposit the appropriate coin to pay for the connection, the operator being informed of the amount deposited by the usual audible signals produced by the coins as they pass on down into the collection box.

What is claimed is:

1. In a multi-coin telephone paystation for use in conjunction with automatic telephone substation, apparatus, signalling devices actuated by coins deposited therein to pay for toll calls, and other mechanism actuated by a coin deposited therein following the response of a called subscriber to permit the calling subscriber to converse with the called party.

2. In a multi-coin telephone paystation device for use in conjunction with and as a part

of a substation of an automatic telephone system, a coin collection box which receives all coins deposited, means being provided for necessitating the deposit of a coin therein only after a subscriber, automatically connected with, has responded, or alternatively under supervision of a toll operator when payment for a toll connection is required, and a set of gongs one or more of which are struck by the deposited coin during its course of movement through the device into the coin collection box for advising an operator of the denomination of such coin.

3. In combination with that part of a multi-coin telephone paystation mechanism which receives coins of different sizes and wherein the coins directly mechanically actuate audible signals characteristic of the coins deposited, an automatic telephone substation including the usual talking, signalling, and impulse transmitting instrumentalities, of means for rendering the transmitter ineffective upon response of a party called unless such party is an operator and requiring the deposit of a coin to render said means ineffective in case a subscriber has been called, the part of said multi-coin paystation referred to also serving on toll calls as a means whereby an operator may supervise deposits made for toll connections.

4. In combination with a multi-coin telephone paystation mechanism having coin-operated signal means, circuit arrangements for permitting a connection to be established, prior to the deposit of a coin, means operative contingent upon the called subscriber's response to short circuit the transmitter of the said paystation telephone, and means actuated by a coin after it actuates said signal means for removing said short circuit.

5. In combination with a telephone substation of an automatic telephone system, and with that part of a multi-coin paystation containing coin actuated signals, a coin holding receptacle having a permanently open chute connecting it with the part of the multi-coin paystation referred to, so that all coins deposited will immediately pass on into said receptacle, means operative contingent on the response of a called subscriber, but not operable upon the response of a toll operator, to short circuit the calling subscriber's transmitter, means actuated by a deposited coin for removing said short circuit to permit conversation, said paystation mechanism being utilized independent of said short-circuiting means for the deposit of coins under the supervision of an operator to pay for toll connections requiring the deposit of one or more coins of the same or of different sizes.

6. In combination with that part of a multi-coin paystation which contains coin actuated signaling devices audible at the paystation in a manner indicative of the coin or coins deposited, of a coin receiving mecha-

nism, of the single coin type, in which responsive to the completion of a connection between two subscribers of an automatic telephone system a coin must be deposited to render the calling subscriber's transmitter operative and in which the deposit of a coin, when an operator is called, is unnecessary, the part of the multi-coin paystation comprising the signals serving as a means whereby an operator can supervise the deposit and collection of coins for toll connections.

7. In a paystation device used in conjunction with a substation of an automatic telephone system, circuit arrangements for permitting all connections to be set up by a calling subscriber prior to the deposit of coins to pay for such connections, means actuated contingent on the response of a subscriber called to render the talking circuit of the calling subscriber ineffective, said means not actuating upon the response of a called operator, coin actuated means for rendering the said transmitter operative in the first instance and a coin actuated signal actuated irrespective of the destination of the call, but being of utility to apprise an operator of the deposit of coins required to pay for connections completed via the operator.

8. In a paystation device for use in conjunction with a substation of an automatic telephone system, a chute for receiving coins to pay for connections completed direct by a subscriber and also for calls completed via an operator, a talking circuit for the calling subscriber made inoperative by the response of a called subscriber, means actuated by a coin thereafter deposited for wiping out the effect produced by the called subscriber's response, and a coin actuated signal for apprising the operator of the coin or coins deposited in said paystation to pay for calls completed via the operator.

9. In a paystation forming a part of the substation apparatus of a subscriber's line, mechanism actuated by a deposited coin following the response of a called subscriber to permit the calling subscriber to converse with the called party, and a signal actuated by the deposit of such coin, in case a toll connection has been set up, to notify the operator that a coin has been deposited.

10. In an automatic telephone system, a subscriber's line, paystation mechanism for said line including a coin chute for receiving coins deposited subsequent to the response of a called subscriber, means actuated by the deposited coin to permit the calling subscriber to converse with the responding subscriber, and a signal actuated by such coin to apprise an operator of its having been deposited in case the call is being set up via an operator.

11. In a telephone system wherein calling subscribers directly set up connections to cer-

tain called subscribers and set up connections via an operator to other called subscribers, a paystation mechanism including a coin actuated device actuated whenever a coin is deposited in the paystation, a second coin actuated device comprising a group of gongs one or more of which are also actuated whenever a coin is deposited in the paystation when a call has been extended via an operator to notify the operator as to the coin or coins deposited, and means effective as a result of the operation of the first of said devices to enable the calling subscriber to converse with a subscriber called direct.

10 15 In witness whereof, I hereunto subscribe my name this 4th day of March, A. D. 1929.
